COVER FOR A RECESSED PAPER ROLL HOLDER

Herbert G. H. Stewart, 1221 Franklin St.,
Santa Monica, Calif.

Filed Apr. 28, 1965, Ser. No. 84,992

Term of patent 3½ years

(Cl. D4—3)

The paper roll and fragmentary portion of a wall are shown in broken lines in FIGURE 1 for illustrative purposes only.

I claim:

The ornamental design for a cover for a recessed paper roll holder substantially as shown.
